BRIDGE AND ANALOGOUS CONSTRUCTION

Irvin H. Luke, Evanston, Ill.

Application June 17, 1940, Serial No. 340,869

4 Claims. (Cl. 72—56)

This invention relates to improvements in bridge, viaduct and analogous constructions, and more particularly, has reference to such constructions generally characterized as "rigid frames" which are usually constructed of reinforced concrete or steel and which may be constructed of wood, plywood, plastic materials, etc., or combinations thereof; an important object of the invention being to provide a construction of this kind affording comparatively increased strength, greater economy of materials of construction, increased capacity to resist loads imposed thereupon and strains induced therein; moreover, render possible and practical, the usage of new and modern construction material, such as laminated woods, plywoods and kindred materials in its construction.

Equally important objects of my invention are to effect, in a construction embodying the same, great reduction in dead weight thereof without sacrificing rigidity and strength by the proper use of a skeleton structure in lieu of the well-known and prevalently employed solid constructions; the construction of frames with a shallower crown and haunch depth, hence reducing the cost of building not only the frame structure per se, but also, the costs of foundations, footings, endwalls and wingwalls, and abutments, and reducing, to a great extent, the amount of excavating required for the lower roadway as well as for the structure proper, and in those instances where head room or clearance is a limiting factor, rendering a rigid frame design embodying the invention, advantageous and feasible where otherwise, it would be impractical or impossible to build.

Another object of my invention resides in the construction of a bridge including upper and lower roadways wherein the lower roadway structure serves in a dual capacity, i. e., as a roadway and as a tie member to resist the tendency of the construction endwalls, legs and possibly footings, to move horizontally or substantially horizontally away from the roadway when the dead or live loads of the bridge or structure are transmitted thereto.

Other objects of the invention will be in part obvious and in part pointed out hereinafter.

Structures of the rigid frame type have only been effected during recent years and usually, are of solid massive reinforced concrete construction. This solid type of rigid frame results in an inefficient use and waste of materials and places a tremendous burden of dead weight on the frame structure proper and on its footings.

In contra-distinction to types of this sort, my invention provides a skeleton construction of ribs, slabs, walls and beams placed and cast together monolithically where needed and only where required to take the stresses and forces existing in the frame. Thus, due to the areas and sections of concrete eliminated, a great amount of weight is avoided by the improved bridge structure and by the same token, the incident costs thereof eliminated.

A concrete bridge or structure spanning an opening or space is composed of a beam, girder, truss or slab. In reinforced concrete, only about one-third of the depth of the beam or slab, on the compression side, is utilized in resisting the compressive stresses, set up by a load or force superimposed on the structure; the tensile stresses are resisted by steel set in the opposite side of the beam or slab near its surface, and 15 the concrete section of the slab or beam itself, from tensile steel to compressive face, resists shear or the tendency of the beam or slab to separate or slip along a longitudinal plane, or to crack diagonally or vertically on a plane normal to the beam. The teachings of my invention have to do with the elimination of the section of concrete not useful in carrying the compressive forces of the beam or slab and allowing only enough solid section to remain to properly resist the shearing stresses and to embed the tensile rods and to provide sufficient bond for the same as well as to cover and encase the rods used for extra shear resistance when such are required; and the particular method of framing, 20 monolithically or otherwise, by placing slabs, beams and other sections with reinforcement to carry the stresses peculiar to the particular rigid frame comprehending my invention.

In order that the invention and its mode of 40 operation may be readily understood by those skilled in the art to which it appertains, I have in the accompanying drawings and the detailed description based thereupon, set out one embodiment of my invention.

45 In these drawings:

Figure 1 is a side elevation of the improved bridge with the reinforcements of the beams, legs, footings and lower roadway or deck schematically shown in association therewith, and 50 the adjacent earth fill shown in section.

Figure 2 is a vertical section through the bridge construction taken along the line 2—2 of Figure 5, looking in the direction in which the arrows point, without showing the arrangement of reinforcing means.

Figure 3 is a fragmentary vertical transverse section taken on line 3—3 of Figure 1, looking in the direction in which the arrows point.

Figure 4 is a similar section taken on the line 4—4 of Figure 1, looking in the direction in which the arrows point.

Figure 5 is a fragmentary view, partly in top plan and partly in section, taken on the line 5—5 of Figure 2, looking in the direction in which the arrows point, some of the reinforcing rods for the upper deck being schematically shown in association with said upper deck.

Figure 6 is a horizontal fragmentary section taken on the line 6—6 of Figure 1, looking in the direction in which the arrows point.

Figure 7 is a similar section taken on line 7—7 of Figure 1, looking in the direction in which the arrows point.

Figure 8 is a like section taken on the line 8—8 of Figure 1, looking in the direction in which the arrows point, and also illustrating, in top view, a portion of the lower roadway or deck, certain of the reinforcing rods for the lower deck and their arrangement with respect to the footing being schematically shown; and

Figure 9 is a detail section taken on the line 9—9 of Figure 2, looking in the direction in which the arrows point.

Having more particular reference to the drawings, in connection with which like characters of reference will designate corresponding parts throughout, the invention, when used for bridge, viaduct or similar construction comprises a deck or slab 1 adapted to directly receive and carry the paving of a roadway 1'. Reinforcing means, such as rods 2 or the like, are preferably embedded or formed in the deck, enabling the same to properly carry its loads or stresses to longitudinally disposed ribs 3, formed of concrete or other suitable material, arranged in substantially equispaced and parallel relationship. The deck 1 is constructed sufficiently thick to insure carrying of the roadway paving 1' and other superimposed loads; moreover, it acts as the compression section of the ribs 3, i. e., in the central section of the deck, approximately in the region indicated at a. The longitudinal spaced and relatively parallel ribs 3 serve as stiffening members between the bridge endwalls 4 and their adjacent legs 5, and over across the deck span, the ribs 3 also serve to resist shearing stresses, by virtue of their respective cross-sectional areas and with the assistance of shearing rods 6, embedded or formed therein, which said shearing rods may be formed or bent from certain of the mid-span tension horizontal metal 7, to be presently described, or from certain of the haunch negative reinforcing metal 8, also hereinafter described. Other or additional shearing rods 9 may also be provided in the ribs 3.

Haunch thrust slabs 10, projecting towards each other from opposite ends of the bridge construction, particularly from the opposed endwalls 4 thereof, are provided. These haunch thrust slabs 10, which are herein showed to be of concrete construction, are disposed between the opposite end portions of the ribs 3 and are carried by said endwalls 4 adjacent their upper extremities. They each serve to sustain the compressive forces of the ribs 3 over and above the capacity of the lower sections of each of the ribs. Suitable reinforcement is provided in said haunch thrust slabs 10 whereby to render the same efficient to carry those forces which are

induced in the haunch thrust slabs by the ribs 3, approximately in the region indicated at b, and by the same token, to effectually carry any other load which may be imposed thereupon. Also, it will be understood that the haunch thrust slabs reinforcing will assist to prevent shearing between the ribs 3 and said slabs 10.

Referring, particularly, to the endwalls 4 and the legs 5 adjacent thereto, it may be here noted 10 that these elements function to support the entire dead and live load of the bridge, viaduct or other structure, in its transmission to the footings 11 provided under each thereof. The hereinbefore referred to haunch reinforcing metal 8 15 within the legs 5, obviously serve to brace or reinforce the same and their adjacent end-walls 4. As will be noted, this reinforcing metal or rods 8 follow down through the backs or outer sides of each of the legs 5 and are hooked into the respective footings 11. Such construction, in addition to serving as bracing or reinforcing means, also will function to effectually prevent horizontal movement of their respective endwalls 4 and legs 5 away from the lower roadway 16, which 20 movement would otherwise be apt to occur by reason of the application of forces to the endwalls 4 and legs 5. If desired, some of the reinforcing metals or haunch rods 8 may be bent and disposed across the legs 5 and thus, serve as 25 shear reinforcements 12, similar to the shear reinforcements provided in the ribs 3, as hereinbefore described. Moreover, if desired, other rods 14 may be utilized in the legs 5 as shear reinforcement.

30 The endwalls 4, as will be understood, each serve a similar purpose to the legs 5 as do the horizontal haunch thrust slabs 10 to the ribs 3 and additionally, said endwalls 4 afford effectual abutments for retaining the earth 15 of the 35 usual fill. The endwalls 4 shall be properly reinforced to resist these forces coming upon the same.

Inasmuch as the endwalls 4 constitute the compression faces of the legs 5 and have a compressive force in the approximate region indicated at c, or a reaction acting in the vertical direction which meets a horizontal force acting toward said endwalls from the haunch thrust slabs 10, it will be seen that the resultant of 45 these two or combined forces is another force distributed from rib 3 to rib 3 acting upwardly at an angle of approximately 45° in a direction away from the lower roadway 16 (hereinafter more fully described). This latter force is resisted by haunch thrust beams 17 which in turn, 50 are restrained by gaining support at their ends because of embedment thereof in the adjacent ends of the ribs 3 and the tops of the legs 5 which, as will be noted upon reference to Figures 55 1 and 2, join and are of substantially the same width or thickness in this area. That is to say, the haunch thrust beam 17, in each instance, gains its support and restraint in much the same manner as would a beam supported by looping 60 hanger rods around each end—the hanger rods in this particular case being the reinforcing metals or haunch rods 8.

The construction of the haunch thrust beams 65 17, of course, corresponds to that of the haunch thrust slabs 10, the endwalls 4 and legs 5 as well as the deck 1, i. e., they are formed of concrete. Reinforcing, in the form of metal rods 18, is provided in each of the haunch thrust beams 17 70 and such reinforcing is so designed as to carry

forces coming thereonto from the haunch thrust slabs 10 and the endwalls 4 into the junction of the ribs 3, the legs 5 and the haunch reinforce metal or rods 8. In order to resist shears, the beams 17 are provided with stirrup-bars 19 to assist the resistance of the concrete, if required.

Spanning the distance between the lower ends of the endwalls 4, and the legs 5 as well as the respective footings 11, and arranged below the upper span or deck 1, is the lower deck or roadway slab 16, constructed of materials corresponding to that from which the deck 1 is constructed. Roadway tie-rods 20 are embedded in and disposed longitudinally in the lower roadway and have their opposite ends extended into and embedded and anchored, by hooks 20', in the oppositely disposed footings 11. It is of course understood, in this connection, that the opposite ends of the rods in the lower roadway 16 are arranged adjacent the relatively facing sides of the footings 11 in juxtaposed relation. Thus, inasmuch as all of the horizontal forces of the legs 5 or their tendencies to move away from the roadway are transmitted through said legs, and none, through the endwalls 4 unless they are properly designated and of a stiffness sufficient to take horizontal thrust, these horizontal forces are distributed from the bottoms of the legs 5 through the footings or beams 11 to the roadway tie-rods 20 embedded in the lower deck or roadway 16 and anchored by the hooks 20' in said footings 11.

At this point it may be noted that the footings 11 may be each provided with longitudinal reinforcement 21, embedded therein and moreover, that said footings 11, in addition to serving as anchoring media for the opposite ends of the lower deck or roadway 16, will also serve to properly distribute the vertical loads imparted thereto onto the soil or on the piles or caissons or other suitable supporting materials.

If under certain conditions, additional or subsequent bracing or rigidifying of the endwalls 4 and legs 5 should become necessary, I desire to have it understood that such may be effected by the installation of mud-jacks or other suitable or similar means whereby to raise and stress the lower roadway or deck 16 to an extent sufficient to draw the endwalls 4 and the legs 5 together or toward said lower roadway or deck 16, thus correcting settlement or other stresses and creating or recreating a proper stress in the haunch rods or reinforcing metals 8 and other members of the frame.

It is to be understood that my invention contemplates the usage of the frame without the lower roadway or deck 16 and its tie-rods 20; such construction being effected by designing the endwalls 4 of proper section and reinforcing them to restrain the passive and active pressure of the usual earth fill.

Manifestly, the construction shown is capable of further modification and such modification as

is within the scope of my claims, I consider within the spirit of my invention.

I claim:

1. A bridge construction, comprising, in combination opposed endwalls, relatively spaced vertical legs adjacent the outer sides of and connected to said endwalls and extending throughout and above their respective heights, footings arranged below and receiving and supporting said endwalls and legs thereupon, relatively spaced substantially parallel ribs spanning the distance between the endwalls, supported upon the same and the extended upper portions of said legs, and an upper deck received and supported on said ribs, endwalls and legs.
2. A bridge construction, comprising, in combination opposed endwalls, spaced vertically disposed legs adjacent certain of the sides of said endwalls and connected thereto and extending to points above the same, footings below said endwalls and legs receiving and supporting the same thereupon, relatively spaced substantially parallel ribs spanning the distance between the endwalls supported upon the same and the extended upper portions of said legs, an upper deck received and supported on said ribs, endwalls and legs, and a lower deck between said footings and connected thereto.
3. A bridge construction, comprising, in combination opposed spaced endwalls, a plurality of relatively spaced vertically disposed legs adjacent the outer sides of said endwalls connected thereto throughout their respective heights and extending above the same, relatively spaced ribs spanning the distance between the endwalls supported thereon and on said legs, a deck received and supported upon said ribs, horizontal thrust receiving means connected to portions of said ribs and to said endwalls, and an outwardly angled beam on each of the endwalls adjacent their jointures with the horizontal thrust receiving means joined with adjacent portions of said ribs and with said endwalls, portions of said legs and with adjacent portions of said deck.
4. A bridge construction, comprising, in combination opposed and spaced endwalls, vertically disposed and relatively spaced legs integral with the outer sides of said endwalls throughout their respective heights and extending thereabove, footings beneath said endwalls and legs receiving and supporting the same, a plurality of relatively spaced ribs spanning the distance between the endwalls received and supported upon the same and said legs, horizontal thrust receiving means connected to portions of said ribs and to said endwalls, an outwardly angled beam on each said endwalls adjacent their jointures with the horizontal thrust receiving means joined with said ribs and said legs, an upper deck received and supported upon said ribs, connected at its opposite ends to the adjacent portions of said angled beams, and a lower deck between said footings and connected thereto.

IRVIN H. LUKE.
